UNITED STATES PATENT OFFICE.

WILLIAM A. SUELL, OF LOS ANGELES, CALIFORNIA.

WRENCH.

1,197,564.

Specification of Letters Patent. Patented Sept. 5, 1916.

Application filed December 8, 1915. Serial No. 65,851.

To all whom it may concern:

Be it known that I, WILLIAM A. SUELL, a citizen of the United States, residing at Los Angeles, in the county of Los Angeles 5 and State of California, have invented a new and useful Wrench, of which the following is a specification.

My invention relates to wrenches, and consists of an arrangement of wrenches 10 which is particularly adapted for use in connection with an automobile. It is also particularly adapted for use with the automobile now being manufactured by the Ford Motor Company, of Detroit, and its 15 use will be explained in connection with such an automobile.

The principal object of the invention is to provide a wrench by means of which a single workman can readily remove the bolts 20 fastening the transmission case in place without any assistance. This particular application of my invention is illustrated in the drawings, in which:

Figure 1 shows a portion of an automobile, and the method of operating the wrench thereon, a portion of the wrench being shown in section to better illustrate the invention. Fig. 2 is an elevation showing the general shape of the wrench.

30 While the following description applies to the Ford machine, it is obvious that the wrench may be used in various places on any automobile, and that it may have various uses aside from automobiles.

35 The invention consists of a wrench made up of a turning member 11, and a holding member 12. The turning member 11 consists of a turning socket 13 which has an opening 14 formed therein, this opening 40 being square or hexagonal to fit heads 15 formed on bolts 16, or to fit nuts 17 which are threaded on the bolts 16. In the application shown the bolts 16 are used to fasten together flanges 18 and 19 which are formed 45 on the transmission case 20 and the crank case 21. The turning socket 13 is secured to a round shank 23, this shank being bent to form a crank handle 24. A grip 25 is secured to the lower end of the crank handle 24 in such a manner that it turns freely 50 therein, this grip 25 being of such a size that it can be easily and securely held by the fingers of the user. The holding mem-

ber 12 consists of a holding socket 30, this socket 30 having an opening 31 therein 55 which is of such a size and shape as to slip over and securely hold either the bolt head 15, or the nut 17. Secured to the holding socket 30 is a shank 32, this shank being formed of a semi-circular bend 33, a primary straight portion 34, and a secondary straight portion 35. The primary bend is of the proper size and shape to pass around and over a side motor hanger 50 so that it can be used on the forward bolts 51. The 60 dimensions of the various parts are made such that when the sockets 13 and 30 are in place on the nut 17, and the bolt head 15, that the secondary straight portion 35 of the holding member 12 extends under the grip 70 25 in immediate proximity thereto.

The method of operating the invention is as follows: The socket 30 is slipped in place on one of the nuts 17, and the socket 13 is slipped in place on a corresponding bolt 15, 75 the parts then being in the approximate position shown in the drawing. One hand "A" of the user is used to hold the grip 25, and the secondary straight portion 35 as shown in Fig. 1. The other hand "B" of 80 the user seizes the crank handle 24 turning it so that the bolt 15 is rotated and withdrawn from the nut 17.

My invention has a practical utility in connection with the Ford automobile in 85 that it is often necessary to remove the transmission case 20 for the purpose of renewing the friction bands which are carried therein. As the transmission case is located under the floor of the car near the front 90 thereof, it is in a rather inaccessible location, and at the present time it is necessary for two men to perform the operation which is performed with my wrench. It is difficult for a man under the car to reach any of 95 the nuts 17, and impossible for him to reach the nuts 51. One of these men sits inside the car and holds the nut 17 with any standard form of wrench, while the other operator lies under the car and removes the 100 bolt 15 by a similar wrench. By the use of my invention it is possible for a single operator to hold the nuts 17 and remove the bolts 15 from a position beneath the car without the necessity of additional help. 105 In the Ford service stations where large

numbers of these brake bands are regularly removed I have found that my wrench is of very great commercial value.

I claim as my invention:—

5. In a wrench, a turning socket adapted to fit on the head of a bolt, a holding socket adapted to fit on the nut of the same bolt, a crank handle secured to said turning socket, a grip loosely pivoted on said crank

handle, and a curved shank secured to said 10 holding socket and so shaped that it lies adjacent to said grip when said sockets are in place on the nut and bolt.

In testimony whereof, I have hereunto set my hand at Los Angeles, California, this 15 2d day of December, 1915.

WILLIAM A. SUELL.
